W. KIRN

DOOR SASH LATCH

Filed April 9, 1923

Patented June 2, 1925.

1,540,134

UNITED STATES PATENT OFFICE.

WILLIAM KIRN, OF SOLOMON, KANSAS.

DOOR-SASH LATCH.

Application filed April 9, 1923. Serial No. 630,860.

To all whom it may concern:

Be it known that I, WILLIAM KIRN, a citizen of the United States, and resident of Solomon, county of Dickinson, State of Kansas, have invented a certain new and useful Improvement in Door-Sash Latches; of which the following is a complete specification.

This invention relates to locks for sliding doors and more especially a lock of this character which does not employ springs or other relatively delicate or light parts which readily break or get out of order when exposed to the weather and subjected to rough usage.

One object is to produce a lock which is peculiarly appropriate for use in securing the sliding doors of freight and other railroad cars, and warehouses where a simple, sturdy and efficient latch is desirable.

A further object is to produce a lock of the character described which is strong, durable, efficient and inexpensive, and in order that it may be fully understood, reference is to be had to the accompanying drawing, in which:—

Figure 1 is a face view of a lock embodying the invention as it will appear when in use with a barn or other door, where it is desirable to provide unlocking means accessible from the interior as well as the exterior of the building;

Figure 2 is a section on the line II—II of Figure 1;

Figure 3 is a face view of a lock embodying the invention as it will appear when in use for locking a freight car door or the like;

Figure 4 is a section on the line IV—IV of Figure 3;

Figure 5 is a side elevation of a modified form of the latch of the lock; and

Figure 6 is a perspective view of a modified form of keeper for the fulcruming of the latch.

In the said drawing, where like reference characters identify corresponding parts in all of the figures, 1 indicates a building wall adjacent a door opening, and 2 a sliding door for such opening. Secured vertically to the wall of the building adjacent the door opening is an abutment or stiffening bar 3, to which is secured by means of bolts 4 at a suitable height from the ground, a keeper plate 5 formed with a right-angle shaped keeper 6 terminating in an inclined face 7 for guiding a latch hereinafter referred to.

The catch 6 projects inwardly beyond the edge of the door jamb opposite the door opening and is adapted to overlap the edge of the door 2 when the latter is in its closed position. On its inner face the catch 6 is formed with a locking lug 8 providing a recess 9 for the reception of the latch, as will hereinafter appear.

The latch 10 is formed of a resilient iron bar bent to rectangular form (see Figure 5), and one portion 11 intermediate the ends of the bar is bent into contact with the end 12 to form a resilient hinge and then is bent to L-form as at 13 to provide an operating handle, although it may be further bent as at 14, in dotted lines Figure 5, to provide a second rectangular portion, both constructions, however, operating the same.

The portions 11 and 12 which are in contact with each other are retained against a face plate 15 of metal to decrease the frictional resistance of the parts, by means of a bearing member 16 bolted to the door and formed with a recess 17 for the reception of said portions 11 and 12 of the latch. In this connection it will be noted that the plate 15 is bent back on itself as at 15^a, to fill the space between the edge of the door and the face of the lug 8 to prevent undue rattling of the door, as will be readily understood. It will be evident that pivotal movement of the latch 10 around the axes of part 12 and intermediate portion 11 within the bearing member 16 will be resisted by the resilience of the latch bar, as its pivotal action will be around two points which are off-center or eccentric with respect to each other, and such pivotal movement will tend to subject the resilient bar to a twisting strain. In this connection, it is desirable to point out that the latch portion 10 and the handle 13 are bent outwardly away from the door to provide for the necessary limited pivoting action of the latch inward over the lug 8

preliminary to snapping into the recess 9 and engaging the rear end of the lug to maintain the door in latched position.

In order to provide means whereby the lock may be operated from the inside of a building, the inner face of the door, in line with the handle 13, is recessed as at 18 and is formed with an opening 19 for sliding engagement with a rod 20 terminating at its outer end in an eye 21 fitted on the handle 13. The inner end of the rod may be provided with a head 22 for the convenience of the

operator. It will be evident that the latch may be readily released from the keeper by imparting outward movement to the handle 13 and corresponding inward movement to the latch 10 causing it to swing in the recess 9 against the resiliency of the latch members within the keeper 6, until the latch passes beyond the plane of the face of the lug 8, thus freeing the door for sliding movement, as will be readily understood.

In order to provide means for engagement by a padlock (not illustrated) or the like, whereby the door may be secured against opening movement, a hasp 23 is secured to the door at such a point that it will underlie the lug 8 of the keeper 6, and formed in the catch 6 is a perforation 24, the parts being so located with respect to each other that the keeper of a padlock 20 may be readily engaged through the hasp 23 and the opening 24 and retain the door against operation.

The lock, as illustrated in Figures 3 and 4 is adapted more particularly for use on railroad car doors and is similar in all respects to the lock above-described, except that it will be noted the plate 4 is provided with a right-angle shaped extension 25 adapted to brace the abutment bar 3. The end of extension 25 is securely fastened to the side of the car by one or more bolts 26. It will also be evident that with a freight car door it is unnecessary to make provision for the operation of the latch from the interior of the car, as a shipment is usually loaded and then the car sealed until it attains its destination.

The following mechanism is provided for sealing the latch when utilized with a car door: Projecting from the keeper 6 and lying parallel to the car are a pair of ears 27 and 28, the former being the lowermost and having an oblong opening 29 and the latter being formed with a circular opening 30. Engaged through openings 29 and 30 is an inverted J-shaped stop member 31, the long leg of the stop being upset as at 32 to permit passage through opening 29 but to prevent withdrawal through the opening 30 of the ear 26, while the short leg is adapted to pass downwardly through the recess 9 inward of the latch 10, and fill said recess and thus prevent unlatching movement of the latch (see Figure 4). The lower end of the short leg of the stop member projects below the keeper 6 and is formed with a slot 33 for engagement with a car seal 34 of any suitable character, which will encircle the long leg of the stop, as illustrated. It will be apparent from the construction described that it will be impossible to operate the latch to unfasten the door as long as the seal 34 remains unbroken.

As above mentioned, the purpose of the

metal strip 15 secured to a door on which it is desirable to employ a lock embodying the invention, is to provide a suitable bearing surface for the pivoting action of the latch. It has been found, however, that many doors are not equipped with a suitable metal strip and in order to provide a suitable backing and at the same time a keeper for the latch members, it has been found desirable to produce the following device: In Figure 6, a metal plate 35 is bent to form a channel portion 36 to receive the parts 11 and 12 of the latch, and said plate is provided with a tongue portion 37 projecting from one edge of the channel. The tongue portion 37, after the latch members have been engaged in position, will be hammered or otherwise forced downward until its exterior face is flush with the rear face of the plate 35, as shown by the dotted line, Figure 6, the free edge of said tongue being received in a recess 38 for its accommodation. It will be evident that with a device of this character the latch members will be simultaneously retained in position and provided with a suitable metallic backing.

It will be evident that when a door equipped with a lock, embodying the invention is slid shut, that its latch 10, through contact with the inclined face 7 of the keeper 6, will be rocked inwardly against the resistance of its parts 11 and 12 until it has ridden over the lug 8 when it will instantly snap into the recess 9 and be engaged with the rear end of the lug, and securely hold the door in closed position.

It is believed that further recapitulation of the operation of the lock is unnecessary. From the above description it will be apparent that I have produced a device embodying the features of advantage set forth as desirable in the statement of the objects of the invention, and which may be modified in minor particulars without departing from the principle of construction and mode of operation involved.

I claim:

1. A lock structure comprising a keeper, a latch of loop form adapted for engagement with said keeper; the latch being in the form of a continuous bar having two portions of its length adjacent and parallel, and a bearing member encircling said overlapped ends, said parallel portions being adapted to rotate on their own axes.

2. A lock structure comprising a keeper, a latch of loop form adapted for engagement with said keeper; the latch being in the form of a continuous bar having one end overlapped with an intermediate portion, and a bearing member encircling said overlapped portions which are adapted to rotate on their own axes.

3. A lock structure comprising a keeper, a latch of loop form adapted for engage-

ment with said keeper; said loop being pivotally secured at a point intermediate its length, and terminating at one end in an operating handle, the other end of said latch being pivoted eccentric to said intermediate portion.

4. A lock structure comprising a door frame and door, a keeper on said door frame, a latch in loop form secured to the door and being adapted to engage said

keeper; said latch being pivotally secured at a point intermediate its length to the door and terminating at one end in an operating handle, the other end of said latch overlapping and abutting said intermediate portion, and a bearing member for retaining the parts in position.

In witness whereof I hereunto affix my signature.

WILLIAM KIRN.
